UNITED STATES PATENT OFFICE.

EDWARD B. STEELE, OF ROCHESTER, NEW YORK, ASSIGNOR TO QUEEN CITY MATERIAL CO., OF BUFFALO, NEW YORK, A CORPORATION OF NEW YORK.

ENGRAVER'S TRANSFERRING DEVICE.

Application filed April 17, 1922. Serial No. 553,978.

To all whom it may concern:

Be it known that I, EDWARD B. STEELE, a citizen of the United States, residing in Rochester, in the county of Monroe and State of New York, have invented new and useful Improvements in Engravers' Transferring Devices, of which the following is a specification.

This invention relates to an engravers' transferring device whereby an original engraving produced upon one article, such as the handle of a knife, spoon or fork may be transferred upon the handles of similar articles so that the engraving upon these additional articles may be of the same design or form and all located alike and thereby adding to the beauty of the articles as a set.

In transferring devices of this character, as heretofore constructed, a gelatinous pad was employed for receiving the transfer materials which pad was arranged in a holder of such a character that the pad in time would shrink away from the sides thereof, by reason of the pad drying out, which is objectionable on account of a gap being formed between the pad and the sides of the holder into which waste materials would accumulate and this usually lead to the transferring device as a whole being thrown away or discarded for a new one.

It is the object of this invention to provide a transferring device of this character in which the holder and the pad are separate and the parts when assembled for use will not permit of the formation of a channel or groove between the side edge of the pad and the holder when the pad is partially dried out, thereby avoiding the objectionable accumulation of material in such a groove and also permitting of using the same holder over and over again, with new pads which may be replaced for those which have been worn out, thereby reducing the cost of maintaining such a transferring device.

In the accompanying drawings:

Figure 1 is a perspective view of the improved transferring device embodying my invention. Figure 2 is a vertical transverse section of the same taken on line 2—2; Fig. 1.

Similar characters of reference refer to like parts in both figures.

In its general organization the transferring device containing my improvement consists of a pad of gelatinous material, and a holder consisting of a lower cup-shaped body

section which receives the pad and an upper cap-shaped cover section which surrounds the body section and overlaps the transfer pad.

This pad in the preferred construction is made in the form of a circular disk 10 which has flat upper and lower surfaces and a cylindrical upright edge and may be constructed of any suitable gelatinous compound, such as commonly employed by engravers for transferring purposes and generally resembles the compound employed for hectograph duplicating apparatus.

The lower body section of the holder comprises a flat or horizontal bottom 11 which engages with the underside of the transfer pad and an annular upright or upstanding wall 20 which rises from the bottom 11 and extends along the peripheral edge of the pad.

The upper or cover section of the holder comprises a horizontal flange 13 which engages with the marginal part of the upper surface of the transfer pad 10 and a depending annular flange 14 arranged at the outer edge of the flange 13 and surrounding the periphery of the body wall 20 with which it is in sliding engagement. For the purpose of conveniently permitting the body and cover of the holder to be separated, an annular bead 12 is arranged at the corner between the upstanding wall 20 and the bottom 11 of the body.

At one place in the cover a gap 15 is formed in the flange 13 which extends from the inner to the outer side of the same, as shown in Fig. 1. On the remaining portion of the inner edge of the flange 13 the same is provided with a plurality of gage notches 16 which are preferably of V-shaped form, as shown in Fig. 1, although the same may be of any other desired shape to suit the work which is to be engraved. On the upper surface of the flange 13 the same is provided with a plurality of pockets in which materials may be stored which are used during the operation of producing transfers of designs upon different articles, for instance, on the end portions of the flange, the same may be provided with comparatively deep pockets 17, 17, one of which may contain a supply of grease or tallow and the other a supply of white chalk, and between these end pockets may be arranged additional intermediate pockets 18 which are adapted to receive powder, wax, or other

materials of different colors which may be desirable for engraving transfers on articles of different kinds of material. On its underside the flange of the cover is provided 5 with one or more spurs 19 which enter the upper side of the transfer pad 10 and prevent the latter from becoming displaced with reference to the gage notches 16 when the pad shrinks or dries out more or less and 10 forms a gap between its periphery and the bore of the body wall 20.

In the use of this device an engraver first 15 engravess the desired letter or other device on the handle of one of the articles of a set, such as a spoon and then fills the engraved portion with a chalk of suitable color. The handle of the article is then placed with the 20 engraved surface downwardly upon the top of the transfer pad with the outer end of the handle in engagement with one of the gage 25 notches and the inner part of the handle arranged in the gap 15 so that the bowl of the spoon is arranged outside of the transfer device, as shown in Fig. 1. Upon pressing the engraved surface on the handle of the article while in this position downwardly upon the pad some of the chalk or transfer material in the engraving will be deposited upon the upper surface of the pad, after 30 which additional impressions may be made from the same engraved portion of the handle by engaging the same successively with one or more of the remaining gage notches 16 in the manner just described and pressing the same downwardly so as to leave the chalk mark upon the upper surface of the pad adjacent to the edge of the gage notches. The additional articles to be engraved, such 35 for instance as spoons, are now first coated with a thin film of grease, wax or tallow and then pressed downwardly upon the impression sections of the pad 10 upon which the designs have been previously deposited by means of chalk whereby these additional articles will pick up the chalk impressions in 40 exactly the same location on the article as they were on the original by reason of the article being held in the gage notches 16 while the impressions are produced thereon. 45 After each article has been thus impressed with the design the same may be engraved in the usual manner and these engravings will be necessarily all located in the same place so that the set of articles are engraved 50 uniformly.

The height of the wall 20 and the rim 14 of the holder is preferably less than the thickness of the pad 10, as shown in Fig. 2, so as to permit the pad to shrink vertically 55 to a considerable extent without permitting the upper side of the pad to shrink away from the underside of the flange 13 by the time the lower edge of the rim 14 engages with the bead 12.

60 The flange 13 is also made of ample width

so that during the maximum shrinking of the pad 10 in a radial direction, this flange will always overlap the pad on the upper side of its marginal part and prevent the formation of any groove or crevice between 70 the upper side of the pad and the gage flange 13 in which materials are liable to accumulate.

As a whole, this device is very simple and compact in construction, it can be produced 75 at low cost and when the pad is either worn out, or dried up to such an extent that the same is of no further use, it may be discarded and replaced by a new one, thus enabling the same holder to be used continuously with different pads and thereby effect 80 a considerable economy.

I claim as my invention:

1. An engraver's transferring device, comprising a transfer pad, and a holder for said 85 pad having a flange overlapping the upper side of said pad and provided with a gage.

2. An engraver's transferring device comprising a transfer pad, and a holder for said pad comprising a lower cup-shaped body 90 which receives said pad, and an upper cap-shaped cover which encloses said body and overlaps said pad and which is provided with a plurality of gages.

3. An engraver's transferring device comprising a transfer pad, and a holder for said pad comprising a lower cup-shaped body which receives said pad, and an upper cap-shaped cover which encloses said body and overlaps said pad and which is provided 100 with spurs engaging said pad.

4. An engraver's transferring device comprising a transfer pad, and a holder having a lower body section which consists of a horizontal bottom engaging with the underside of the pad and an upstanding wall, and an upper cover section having a top flange which engages with the marginal part of the upper side of said pad and which is provided with a plurality of gages and a rim 110 depending from said top flange.

5. An engraver's transferring device comprising a transfer pad, and a holder having a lower body section which consists of a horizontal bottom engaging with the underside of the pad and an upstanding wall arranged along the edge of said pad, and an upper cover section having a top flange which engages with the marginal part of the upper side of said pad and a rim depending 120 from said top flange and surrounding said wall said flange being provided on its underside with spurs entering the upper side of said pad.

6. An engraver's transferring device comprising a transfer pad, a holder having a lower body section which consists of a horizontal bottom engaging with the underside of the pad, and an upstanding wall arranged along the edge of said pad, and an upper 130

cover section having a top flange which engages with the marginal part of the upper side of said pad and a rim depending from said top flange and surrounding said wall, 5 said flange being provided at one place in the circumference of said rim with a gap extending from the inner to the outer side of the flange.

7. An engraver's transferring device comprising a transfer pad, and a holder having a lower body section which consists of a horizontal bottom engaging with the under- 10 side of the pad, an upstanding wall arranged along the edge of said pad, and an upper cover section having a top flange which engages with the marginal part of the upper side of said pad and a rim depending from said top flange and surrounding said wall, 15 said flange being provided at one place in the circumference of said rim with a gap extending from the inner to the outer side of the flange, and the upper side of said flange being provided with a plurality of 20 pockets for the reception of transfer materials.

of the flange, and the inner edge of the flange being provided with a plurality of gage notches.

8. An engraver's transferring device comprising a transfer pad, and a holder having a lower body section which consists of a horizontal bottom, engaging with the under- 25 side of the pad, and an upstanding wall ar- 30 ranged along the edge of said pad, and an upper cover section having a top flange which engages with the marginal part of the upper side of said pad and a rim depending from said top flange and surrounding said wall, 35 said flange being provided at one place in the circumference of said rim with a gap extending from the inner to the outer side of the flange, and the upper side of said flange being provided with a plurality of 40 pockets for the reception of transfer ma- terials.

EDWARD B. STEELE.
